UNITED STATES PATENT OFFICE.

ALBERT N. WRIGHT, OF ROCHESTER, NEW YORK.

HANGER FOR USE IN CONCRETE CONSTRUCTION.

1,136,460.

Specification of Letters Patent. Patented Apr. 20, 1915.

Application filed January 24, 1908. Serial No. 412,394.

To all whom it may concern:

Be it known that I, ALBERT N. WRIGHT, of Rochester, in the county of Monroe and State of New York, have invented a certain 5 new and useful Hanger for Use in Concrete Construction, of which the following is a specification.

My invention has for its object the production of a hanger for use in concrete construction, which is particularly simple in 10 construction and capable of more or less adjustment.

In describing this invention, reference is had to the accompanying drawing in which 15 like characters designate corresponding parts in all the views.

Figure 1 is a sectional view of my hanger showing the same embedded in the concrete. Fig. 2 is a plan view of the hanger, a part 20 being removed. Fig. 3 is a cross sectional view of the body of my hanger.

This hanger comprises a body 1 designed to be embedded in the concrete, and an engaging member or hanger-proper 2, suspended from the body. The body is preferably elongated and formed with outwardly inclined or flared sides and ends 3 and 4, extending above the part of the body directly supporting the engaging member 2, 25 for facilitating the securing of the body in the concrete, said body being open at its top for permitting the concrete to engage inner and outer sides thereof. As shown, the ends 4 are of greater height than the 30 central portions of the sides 3, and, together with the end portions 5 of the sides, form wings having channels in which the concrete runs when poured. The body is also formed with an elongated chamber 6 in its lower 35 portion, the chamber having an open top and a slot 7 in its bottom midway between the sides of said chamber. A supporting member, here shown as a non-circular head or nut 8, is located in said chamber, the sides 40 of the nut engaging the sides of the chamber, and the threaded opening 9 thereof, being aligned with the slot. The chamber is covered by a plate 10 which rests on a ledge 11 surrounding the top of the chamber, and 45 prevents the concrete from entering the chamber.

12 is a connecting element projecting through the slot 7 and preferably detachably connected to both members 2 and 8. 50 As here shown, the engaging member 2 is formed with an eye 13 for receiving a pipe

or other part to be supported by the hanger, and with a threaded passage 14 for receiving the outer threaded end of the connecting element, said engaging member being adjustable lengthwise of the connecting element, toward and from the body, and adjustable laterally relatively to the body, by reason of the ability of the nut to be moved in the chamber 6 along the slot 7.

The upper end of the connecting member is threaded and enters the threaded opening of the nut and the end face thereof engages the plate 10 and acts as a set screw for holding the member 12 in its adjusted position relatively to the slot 7. It is obvious, however, that a bolt may be substituted for the nut and connecting element.

In placing the hanger in position, it is secured to the wood false work before the 75 pouring of the concrete, by a bolt passing through the wood false work and into the nut 8, and when the wood false work is removed, the engaging member and connecting member are substituted for the bolt. 80

What I claim is:—

1. A hanger for use in concrete construction comprising a body designed to be embedded in the concrete, the body being formed with an elongated chamber opening through the top of the body and having side walls, the body being also formed with a slot opening through the bottom of the chamber into the same and with a ledge around the upper side of the chamber and walls rising from the ledge, a cover plate for the top of the chamber, the cover plate resting on the ledge and engaging at its edges the last-mentioned walls, a supporting member located in the chamber and adjustable along the slot and engaging the side walls of the chamber, and an engaging member suspended from the supporting member and detachably connected through the slot thereto, substantially as and for the purpose described.

2. A hanger for use in concrete construction comprising a body designed to be embedded in the concrete, the body being formed with a chamber having a slot in its bottom and a cover for the chamber, the cover being immovable when the hanger is embedded in the concrete, a nut in the chamber having its threaded opening aligned with the slot, a supporting member extending through the slot and threading into the nut and turning into engagement with the cover

to hold said member in its adjusted position relatively to the slot, and an extension member adjustable lengthwise of the supporting member, substantially as and for the purpose specified.

3. A hanger for use in concrete construction comprising a body designed to be embedded in the concrete, the body being formed with a chamber having a slot in its bottom and an open upper side, a cover removable for closing the said upper side of the chamber, a nut in the chamber having its threaded opening alined with the slot, and a supporting member extending through the slot and threading into the nut and into engagement with said cover to hold said member in its adjusted position relatively to the slot, substantially as and for the purpose specified.

20 4. A hanger for use in concrete construction comprising a body designed to be embedded in the concrete, the body being formed with side walls, an elongated chamber having an elongated slot in its bottom and an open upper side, a nut in the chamber engaging the side walls thereof and having its threaded opening alined with the slot, a plate arranged to cover the open upper side, said plate being designed to have contact therewith for preventing the dislodgement of the same and resting on surfaces on opposite sides of the upper edges of its side walls, and a supporting member extending through and adjustable lengthwise of the slot and threading into the nut and movable into engagement with the plate and hence holding the nut and supporting member in its adjusted position relatively to the slot and chamber, substantially as and for the purpose set forth.

5. A hanger for use in concrete construction comprising an elongated body designed to be embedded in the concrete, said body being formed with outwardly inclined sides and ends, the ends being of greater height than the central portions of the sides and together with the end portions of the sides forming wings having channels, an engaging member and means associated with the body for supporting the engaging member, substantially as and for the purpose described.

6. A hanger for use in concrete construction, comprising a body designed to be embedded in the concrete, said body being formed with outwardly flared sides and ends

and with a chamber near its bottom, the chamber being open at its top and having a slot in its bottom, a plate covering the top 60 of the chamber and located near the bases of the sides and ends, a supporting member located in the chamber and adjustable along the slot, and an engaging member suspended from the supporting member and connected 65 through the slot thereto, substantially as and for the purpose described.

7. A hanger for use in concrete construction, comprising a body designed to be embedded in the concrete, said body being 70 formed with outwardly flared sides and ends and with a chamber near its bottom, the chamber being open at its top and having a slot in its bottom, the body being formed interiorly with a ledge or support- 75 ing means for a cover plate near the open top of the chamber, a plate covering the top of the chamber and resting on the ledge, a supporting member located in the chamber and adjustable along the slot, and an engag- 80 ing member suspended from the supporting member and connected through the slot thereto, substantially as and for the purpose set forth.

8. A hanger for use in concrete construc- 85 tion comprising an elongated body designed to be embedded in the concrete, the body being formed with outwardly and upwardly inclined sides and ends, the ends being of greater height than the central portions of 90 the sides, and together with the end portions of the sides forming wings having channels, the body being also formed with a chamber in its lower portion the chamber having an open top and a slot in its bottom, 95 and the body also having a ledge surrounding the open top of the chamber, the ledge being located below the upper edges of the sides of the body, a plate covering the top of the chamber and resting on said ledge, a 100 supporting member located in the chamber and adjustable along the slot, and an engaging member connected to the supporting member through the slot, substantially as and for the purpose set forth.

In testimony whereof, I have hereunto signed my name in the presence of two attesting witnesses, at Rochester, in the county of Monroe, in the State of New York, this 21st day of October, 1907.

ALBERT N. WRIGHT.
